(57) **CLAIM**

The ornamental design for a clothes rack as shown and described.

DESCRIPTION

1. Clothes Rack
2. Clothes Rack
- 1.1:Perspective;
- 1.2:Front;
- 1.3:Back;
- 1.4:Top;
- 1.5:Bottom;
- 1.6:Right;
- 1.7:Left.
- 2.1:Perspective;
- 2.2:Front;
- 2.3:Back;
- 2.4:Top;
- 2.5:Bottom;
- 2.6:Right;
- 2.7:Left.

No protection is sought for features shown in broken lines, which form no part of the claimed design. The thin linear hatching lines shown in the drawings represent shading only and not surface ornamentation. The double-dashed broken lines within curved dotted brackets represent a symbolic break of indeterminate length in the claimed design. The appearance of any portion of the clothes rack between the symbolic break lines forms no part of the claimed design.
